UNITED STATES PATENT OFFICE

1,978,943

ICE CREAM DIPPER

Ora E. Harris, Kearney, Nebr.

Application January 2, 1934, Serial No. 704,943

1 Claim. (Cl. 107—48)

My present invention relates to an ice cream dipper for molding or dispensing ice cream taken from bulk as the same is received in large receptacles from the place of manufacture and 5 said invention is in the nature of an improvement or refinement of the invention disclosed and claimed in United States Letters Patent 1,896,083 issued to me of date February 7, 1933 and application filed October 20, 1933 under 10 Serial Number 694,460.

To the above end the invention consists of the novel devices and combinations of devices hereinafter described and defined in the claim.

In the accompanying drawing, which illustrates the invention, like characters indicate like parts throughout the several views.

Referring to the drawing:

Fig. 1 is a view of the improved ice cream dipper principally in central longitudinal section 20 with some parts broken away and other parts sectioned; and

Fig. 2 is a bottom plan view of the improved dipper.

The improved ice cream dipper includes a 25 cylindrical cup 3 having an open lower end completely surrounded by a cutting edge. The cup 3, at its upper end, is normally closed by a top or cover 4 having a flange 5 which caps the upper end portion of said cup and is detachably 30 but rigidly secured thereto by screw-threads 6. This top 4 has an upwardly and inwardly contracted central portion 7 that terminates in an 35 upstanding tubular neck 8 axially aligned with the cup 3.

35 A tubular stem 9, at its lower end, is fitted in the neck 8 and rigidly secured thereto. A cylindrical head 10 caps the stem 9, at its upper end, and is rigidly secured thereto. This head 10 is provided with a radially projecting handle 40 11 and a diametrically opposite finger piece 12. Also integrally formed with the head 10 is a second finger piece 13 located directly under the handle 11 and spaced therefrom.

A reciprocating ejector 14 is mounted in the 45 cup 3 and has a disk-like body with a convex upper face and a concave under face. On the under side of the ejector 14 is a die 15 in the form of a boss and a plurality of penetrating bosses 16. The die 15 is at the center of the 50 ejector 14 and the bosses 16 are radially outward of said die and spaced substantially equal distances apart circumferentially about the ejector 14.

An operating rod 17 is provided for the ejector 14 and is rigidly secured, at its lower end,

to said ejector at the center thereof. This ejector or operating rod 17 is round, extends loosely endwise through the stem 9, and a guide hole in the head 10. A knurled knob or finger piece 18 is detachably secured to the ejector rod 17, at its 60 upper end, outwardly of the head 10 and its engagement with said head limits the ejecting movement of the ejector 14. An air hole 19 is formed in the central head portion 7.

Within the cup 3 is a depending breaker prong 65 or blade 20 having at its upper end a screw-threaded stud 21 that extends through a hole in the top 4 and has applied thereto a thumb-nut 22. This thumb-nut 22 holds the breaker prong 20 with its upper end tightly drawn 70 against the under side of the top 4 and thereby securely holds said prong from turning about the axis of the screw stud 21. As shown, the breaker prong 20 is flat, relatively thin and extends edgewise radially from the axis of the 75 cup 3. The lower end portion of the breaker prong 20 is tapered to a long sharp point.

Formed in the perimeter of the ejector 14 is a radially extended notch 23 through which the breaker prong 20 extends and connects the ejector 14 to the cup 3 for common turning therewith but at the same time permits free reciprocating movement of said ejector in the cup 3.

In dispensing ice cream by means of the improved dipper, said dipper is held by the handle 80 11 and finger pieces 12 and 13 and the cup 3 pressed into bulk ice cream to cut a cylindrical cake therefrom. The cake of ice cream while entering the cup lifts the ejector 14 until stopped by its engagement with the top 4. Air caged in 85 the cup 3 between the cake of ice cream and the top 4 will escape through the air hole 19. After the ejector has been stopped by its engagement with the top 4 further pressure on the cup 3 into the bulk ice cream will force the die 90 15 and bosses 16 into the top of the cake. While the cup 3 is being forced into the bulk ice cream the breaker prong 20 which, as shown, is edgewise spaced from the shell of the cup 3, penetrates the cake. When the cup 3 is completely filled with ice cream said cup is given a 100 slight turn about its axis in the bulk ice cream to break the cake at the cutting edge of the cup 3 from said bulk. During this turning movement of the cup 3 the ejector 14 is held by the breaker prong 20 for common turning movement with 105 said cup. One function of the breaker prong 20 is to cause the cake to turn with the cup and thereby materially assist in breaking the cake from the bulk ice cream. Another function of 110

the breaker prong 20 is to assist in holding the cake in the cup 3 while the dipper is being removed from the bulk ice cream.

The bosses 16, which are pressed into the top 5 of the cake, also assist in holding the cake for common turning movement with the ejector 14, and hence, the cup 3. After the cake has been broken from the bulk the dipper is lifted to extract said cake from the bulk and said cake 10 thereafter removed from the cup 3 by operating the ejector 14. The purpose of the die 15 is to form a seat or depression in the top of a cake in which a piece of candy or fruit may be placed.

15 Heretofore it has been difficult to keep ice 20 cream dippers clean and in a sanitary condition. To clean the dipper, which is the subject matter thereof may be very quickly and easily separated by unscrewing the top 4 from the cup 3 and thereafter removing the breaker prong 20 from the top 4 by releasing the thumb-nut 22,

The ejector 14 may also be removed from the assembled dipper by unscrewing the finger piece 18 and drawing the operating rod 17 from the stem 9. With the parts thus separated the dipper may be easily and thoroughly cleaned.

What I claim is:

In an ice cream dipper, a tubular handle having a centrally recessed head at one end, said head having annular means for detachably securing a thrust cup thereto, an ejector reciprocatably mounted in said handle and having a disk-like body portion receivable within said head and movable through a cup, and means carried by said head to one side of its centrally recessed portion for detachably receiving a cake breaker, said disk-like body portion being formed with an opening coincident with said last mentioned means, whereby a cake breaker may be inserted or removed from said head through said opening in said disk-like portion of the ejector.
